Patented Nov. 4, 1975

237,453

WIRE STRIPPER

Joseph Perrino, Rehoboth, Mass., assignor to Micro
Electronics, Inc., Newport, R.I.

Filed Apr. 8, 1974, Ser. No. 459,128

Term of patent 14 years

Int. Cl. D8—05

U.S. Cl. D8—56

FIG. 1

FIG. 2

FIG. 3

FIG. 4

FIG. 5

FIG. 6

FIG. 1 is a side elevational view showing my new design for a wire stripper;

FIG. 2 is an elevational view thereof of the side opposite to that illustrated in FIG. 1;

FIG. 3 is a top plan view thereof;

FIG. 4 is a bottom plan view thereof;

FIG. 5 is a front elevational view thereof; and

FIG. 6 is a rear elevational view thereof.

I claim:

The ornamental design for a wire stripper, substantially as shown.
